A. F. MARVIN

CLOTHES DRYING RACK

Filed Feb. 19, 1923

UNITED STATES PATENT OFFICE.

ARTHUR F. MARVIN, OF HIGHLAND PARK, MICHIGAN.

CLOTHES-DRYING RACK.

Application filed February 19, 1923. Serial No. 620,019.

To all whom it may concern:

Be it known that I, ARTHUR F. MARVIN, a citizen of the United States, residing at Highland Park, in the county of Wayne 5 and State of Michigan, have invented a new and useful Clothes-Drying Rack, of which the following is a specification.

This invention is a foldable drying rack for laundry and similar use.

- 10 One of the objects of the invention is to provide a rack of simple construction and maximum capacity, which will occupy a minimum of space when in use, and which may be folded up compactly for convenient 15 storage when not in use. A further object is to provide a rack having means for bracing the relatively movable parts when in use, whereby a rigid and stable structure is provided. A further object is to provide a rack 20 of the character mentioned provided with brace members, so disposed as to be readily accessible but normally locked against accidental displacement, when the rack is in either its open or its closed position.
- 25 The invention will be hereinafter fully set forth and particularly pointed out in the claims.

In the accompanying drawing:—

- 30 Figure 1 is a top plan view illustrating a rack constructed in accordance with the invention. Figure 2 is a side elevation with the parts open and ready for use. Figure 3 is a bottom plan view of the rack when folded for storage. Figure 4 is a longitudinal sectional view illustrating one of the locking members. Figure 5 is a transverse section on the line 5—5, Figure 1.

Referring to the drawing, 10 designates a rectangular frame, constructed of suitable 40 material, the end bars of the same having holes or perforations, through which is threaded a continuous line 11, whereby a plurality of parallel strands are surrounded between said end bars. The frame 10 is 45 stiffened by means of diagonally disposed brace bars 12, connecting the side and end bars contiguous to the corners.

Two leg members are provided, each consisting of a pair of legs 13, pivotally connected at their ends to the side bars of the frame 10, as indicated at 14, the lower ends of each pair of legs 13 being connected by a brace bar 15. It will be noted that the 50 legs 13 of the one leg member are pivoted 55 to the exterior of the side bars of the frame 10, and the legs 13 of the other leg mem-

ber are pivoted to the inside of said side bars, as shown.

When the leg members are in open position to support the frame 10, they are braced 60 and rigidly held in such position by means of pivoted brace rods 16. As shown in the drawing, said brace rods are secured in pairs. to the respective side bars of the frame 10, by means of pairs of approximately 65 U-shaped keepers 17, which are attached to said side bars. Pivotal mounted in each keeper is a lock 18, having a free handlelike or operating end, normally pressed outwardly by a spring 19. The spring 19 is illustrated as a common type of bent leaf spring which reacts against the top of the keeper 17 and locking bar 18, so as to normally press the free end of the latter outwardly as clearly shown in the drawings. Near 70 either end of rod 16 an angle of ninety degrees (90°) is formed in such manner that the portions 20 and 21 thus deflected lie in the same plane. The portion 20 extends through keeper 17 and the lock 18 to provide 75 the pivoted support for the lock. The end of portion 20 is peened or headed thus remaining permanently in position. Each lock 18 is provided with an opening 22, 80 which is adapted to be brought into register 85 with a similar opening 23, in the keeper, by pressing in the free end of the lock 18 against the tension of its spring 19. It is obvious that after the portion 21 of a brace rod 16 has been inserted through the 90 registering openings 22 and 23, the spring 19 will force the lock 18 outwardly in a manner tending to move said openings out of register, thereby holding said portion 21 95 firmly locked against accidental withdrawal. It will be noted that each side bar of the frame 10 is provided with a pair of keepers 17 and locks 18, so that when the rack is folded for storage the portion 21 of each brace rod 16, may be locked and held by the 100 lock 18 of the other keeper on the same side of the frame.

Each leg 13 is also provided with a keeper 17 and a lock 18, said keeper and lock having openings 22 and 23 adapted to be brought 105 into register to receive the offset or bent portion 21 of a brace rod 16, the structure being identical with that used on the side bars, except that the pivot 24 for the lock 18 is in the position illustrated in dotted 110 lines in Figure 5. In lieu of using a portion of the brace rod as a pivot, it is of course

necessary to employ a separate pivot in the leg lock.

In practice when the rack is not in use, the parts are folded in the position illustrated in Figure 3, the pivoted brace rods 16 being located in the respective keepers 17, carried by the frame 10, and disposed in pairs as shown. That is, one brace rod of each pair is pivoted so as to lie on the outside of the keepers 17, and the other brace rod of the same pair is pivoted to lie on the inside of said keepers. In this way the brace rods are held locked against accidental displacement, so as not to interfere with the folding or unfolding of the rack, and they are so disposed that they will not catch into other objects when the rack is placed in storage. When it is desired to use the rack, the leg members are swung to open position on their pivots 14, until they stand at right angles to the frame 10. The portion 21 of each brace rod is then disengaged from the keeper 17 and lock 18 carried by the frame, and engaged with the corresponding lock and keeper carried by the contiguous leg member. It will be noted that the keepers 17 carried by the frame 10, are located contiguous to the corners of the frame so that they may be conveniently engaged with the keepers on the legs.

From what has been said it will readily be seen that by stringing the line 11 in the manner described, a maximum capacity is provided to accommodate the garments to be suspended from the rack, and yet the device occupies but a minimum of space when not in use. By arranging the keepers and brace rods in pairs, the parts are rigidly braced to provide a very stable structure when in use, and yet the device may be folded up compactly for convenient storage when not in use. By providing the locks for the brace rods, the latter will not become accidentally disengaged, when the rack is in either its open position or its closed position, thereby insuring stability of the rack when in use.

Having thus explained the nature of the invention and described an operative manner of constructing and using the same, although without attempting to set forth all of the forms in which it may be made, or all of the forms of its use, what is claimed is:—

55 1. A clothes drying rack of the character described comprising a rectangular frame, a pair of legs pivoted to the inside of said frame near one end, a pair of legs pivoted to the outside of said frame near the other end, spring locking devices each on one side of a leg, and brace rods each pivoted to the under side of a side bar of said frame and each having its free end shaped to engage one of said locking devices.

60 2. A clothes drying rack of the character

described comprising a rectangular frame, legs pivoted to the side bars of said frame, pairs of keepers secured to the side bars of said frame, pairs of brace rods each pivoted at one end to a keeper, and locking means associated with each keeper to engage the free end of a brace rod pivoted to the other keeper, said legs also having means to engage the said free ends of said brace rods. 70

3. A clothes drying rack of the character described comprising a rectangular frame, legs pivoted to the side bars of said frame, pairs of keepers secured to the side bars of said frame, pairs of brace rods each pivoted at one end to a keeper, a locking member associated with each keeper and each movably mounted on the pivoted part of one of said rods, said locking members being positioned to engage the free end of a brace rod pivoted to the other keeper, and means on each leg positioned to also engage the free ends of respective brace rods when they have been disengaged from the locking means on the frame. 75

4. A clothes drying rack comprising a frame, legs pivoted thereto, pairs of keepers secured to the side bars of said frame, pairs of brace rods each bent at one end, the bent end of each rod being pivoted to a keeper, locking members pivotally mounted in the respective keepers, said locking members and keepers having complementary means to engage the free ends of said brace rods when the rack is collapsed, and means on said legs positioned to be engaged by the free ends of said brace rods when the rack is in open position. 90

5. A clothes drying rack comprising a frame, legs pivoted thereto, keepers secured to the side bars of said frame, brace rods each bent at one end and having said bent end extended transversely through a keeper, and locking members located within the respective keepers and pivotally mounted upon the bent ends of said brace rods, said locking members and keepers having complementary means to engage the free ends of the brace rods when the rack is collapsed, and means on said legs positioned to be engaged by the free ends of said brace rods when the rack is in open position. 100

6. A clothes drying rack comprising a frame, legs pivoted thereto, pairs of keepers secured to the side bars of said frame, pairs of brace rods each having bent ends, one bent end of each rod being pivoted to a keeper, spring-pressed locking members pivotally mounted in the respective keepers, the locking members and keepers having holes positioned to register to receive the free bent ends of said brace rods, when the legs are collapsed, and means on said legs also positioned to be engaged by said free bent ends when the legs are in open position. 110

7. A clothes drying rack comprising a frame, legs pivoted to the frame, keepers secured to the respective legs, spring-pressed locking devices pivotally supported by said keepers, each locking device and keeper having openings positioned to register, and brace rods each pivotally con-

ected at one end to the frame and having their free ends shaped to enter said registering openings.

10 In testimony whereof I have hereunto set my hand.

ARTHUR F. MARVIN.
